(57) **CLAIM**

The ornamental design for a respiratory mask cushion, as
shown and described.

DESCRIPTION

FIG. 1 is a front perspective view of a respiratory mask cushion according to our design;

FIG. 2 is a reverse perspective view thereof;

FIG. 3 is a front view thereof;

FIG. 4 is a rear view thereof;

FIG. 5 is a top view thereof;

FIG. 6 is a bottom view thereof;

FIG. 7 is a left side view thereof; and,

FIG. 8 is a right side view thereof.

The broken lines illustrate environmental structure of the
respiratory mask cushion which forms no part of the claimed
design.
